LAY MOTION FOR LOOMS

Robert J. Bartholomew, Philadelphia, Pa., assignor to Fletcher Works, Incorporated, Philadelphia, Pa., a corporation of Pennsylvania

Application June 2, 1943, Serial No. 489,407

17 Claims. (Cl. 139—188)

This invention relates to the lay motions of looms in general; and particularly looms of the so called "narrow fabrics" type, on which tapes, strips of webbing, and such textile fabrics are woven.

The principal object of the invention is to effect a material reduction in the throw of the cranks by which the lay of a loom is oscillated or reciprocated, and thereby provide for an increase in the speed of the loom and a consequent increase in the hourly production of the loom.

In weaving textile fabrics, the warp threads of the fabric are divided into two groups, i. e. an upper group and a lower group, and the positions of these groups are intermittently reversed to form open warp sheds for passage of a shuttle adapted to place weft threads in the respective warp sheds successively, between the front edges of the blades of a reed on the oscillating or reciprocating lay of the loom, and the fell of the fabric, where the weft threads are beat-up by the front edges of the reed blades when the lay attains its extreme forward position.

When the lay is in its extreme backward position, the two groups of warp threads diverge rearwardly from the fell of the fabric and pass through the dents of the reed, at an angle sufficiently wide to afford passage for the shuttle through the open warp shed thus formed.

In order to obtain the necessary movement of the lay from its extreme rearward position to its extreme forward position and vice versa, to beat-up a weft at the fell, and to provide the necessary space for the shuttle to pass through the open warp shed, it has been necessary heretofore, in narrow fabric looms for example, to provide cranks having a throw of approximately four and one-half inches.

In accordance with the principles of the present invention, by use of a novel form of reed and operating mechanism therefor, the throw of the lay-operating cranks may be reduced to approximately one and one-quarter inches, with a corresponding reduction being effected in the travel of the lay.

The reed of the present invention comprises a plurality of laterally spaced blades, each of which includes a front substantially vertical part and rearwardly spaced back part connected by an intermediate substantially horizontal part.

The invention, furthermore, contemplates the use of novel means for reciprocating the reed blades vertically, en masse, in coordination with the oscillations of the lay, whereby, as the lay moves rearwardly the reed blades will be lowered

to a position to permit the shuttle to pass through the newly formed warp shed, above the upper edges of the horizontal connecting portions of the reed blades, and in front of the front vertical edges of the rear parts of the blades; and whereby, as the lay moves forwardly, the reed blades will rise behind the weft laid in the warp shed by the shuttle and effect the beat-up thereof at the fell of the fabric; thus, the travel of the lay is reduced to an extent corresponding to the distance between the front edges of the rear parts of the reed blades, and the front edges of the front and the throw of the cranks which effects oscillation of the lay is reduced accordingly.

In the accompanying drawings:

Fig. 1 is a vertical sectional elevation of sufficient of a loom to illustrate the principles of the present invention, with the lay shown in the back position for passage of a shuttle through the open warp shed;

Fig. 2 is a view similar to Fig. 1, with the lay shown in the forward position, beating up a weft thread at the fell of the fabric;

Fig. 3 is a fragmentary front elevation of the lay as viewed from the plane 3—3, Fig. 1;

Fig. 4 is a fragmentary sectional plan view, as taken on the line 4—4, Fig. 2;

Figs. 5 and 6 are detached perspective views of various elements of the structure shown in Figs.

30 1 to 4 inclusive;

Fig. 7 is a view similar to Fig. 2, showing a modified form of the invention;

Fig. 8 is a view similar to Fig. 3 and illustrating the mechanism of Fig. 7;

Fig. 9 is a sectional plan view taken in the line 9—9, Fig. 8; and

Figs. 10 and 11 are detached perspective views of parts of the mechanism shown in Figs. 7 to 9 inclusive.

40 As shown in Figs. 1, 2 and 3, the lay beam 1 is carried by a plurality of rocker arms 2, spaced apart along the width of the lay beam 1. The lay arms 2 are pivoted at 3 on the frame 4 of the loom, near the level of the floor on which the loom is mounted.

As usual, in narrow fabric looms, the lay beam 1 carries a plurality of shuttle guide blocks 5 which are spaced apart along the width of the lay beam, with a plurality of reed combs interposed between and alternating with the shuttle guide blocks, across the full width of the loom.

In the present instance, the shuttle guide blocks 5, each consist of an upper guideway 6 and a lower guideway 7, which are supported by brackets or plates 8 secured to the back face of

the lay beam 1, and project up above the top face thereof. The upper ends of the brackets 8, 8 are connected by and secured to a top rail 9, in the form of an angle iron in the present instance.

The top rail 9 is also secured to vertical extensions 2a of the rocker arms 2, for rigidity, and in instances where a shuttle guide block 5 may be in line with an intermediate rocker arm 2, the top and bottom guideways 6 and 7 may also be secured to the extension 2a of the rocker arm.

The shuttles 10, as usual, are adapted to reciprocate, or oscillate in cases where arcuate shuttle guides are employed, from one shuttle guide block 5 to the next adjacent shuttle guide block 5 across the intervening reed and warp space, in laying a weft in the open warp shed.

Different types of mechanisms are provided for effecting reciprocation or oscillation of the shuttles. For example, in some instances, "fly" shuttles are used and are moved from one to another of the shuttle guide blocks by fingers projecting vertically from a longitudinally reciprocating bar slidably mounted in a groove formed in the top surface of the lay beam. In other instances, such as in the present case, "rack" shuttles are used and the operating bar is in the form of a gear rack 11, with the teeth of the rack meshing with the teeth of gears 12, 12 which are rotatably supported in the lower shuttle guide ways 7, 7 respectively.

The gears 12, 12 are adapted to mesh with rack teeth 13 formed in the lower sides of the shuttles 10, and as the rack bar 11 reciprocates, in timed relation to the oscillations of the lay, by means not herein shown and which form no part of the present invention, the gears 12, 12 are rotated and move the shuttles 10, 10 in the aforesaid manner, well known in the art.

The lay beam 1 is oscillated by pitmans 15 each of which has one end pivotally connected at 16 to one of the lay arms 2. The opposite end of each pitman 15 is journaled on a crank arm 17 of the crank shaft 18 of the loom.

In the present instance, the throw of the crank arms 17 is reduced to a minimum, as previously noted, and as will be more fully discussed hereinafter. The crank shaft 18 is driven in the usual manner from a line shaft or by an individual motor, as desired, through suitable gearing, or through any suitable speed reduction or variable speed mechanism.

As usual, the warp shed A is formed by raising and lowering one series of warp threads a1 in alternate or other predetermined relation to a second series a2, with one series up and one series down. The warp sheds A are formed and controlled by the usual heddle frames 19, 19, which are operated, in coordination with the reciprocations of the lay beam 1, by ordinary mechanism forming no part of the present invention, for passage of the shuttles 10, for laying a weft b in each of the open warp sheds A, to be subsequently beat-up at the fell x of the fabric y, by reed units 20.

In the present instance, each reed unit 20, between each pair of shuttle guide blocks, 5, 5, is composed of a series of substantially horizontally offset blades 21, one of which is shown in perspective in Fig. 6.

Each offset blade 21 is composed of a rear top vertical section 21a, a front bottom vertical section 21b, and an intermediate substantially horizontal connecting section 21c, all formed as integral parts of the whole.

The blades 21, 21 may be stamped from sheet steel, for example, of any desired gauge, and then

edge-ground or otherwise rendered smooth and free of burrs. If desired, the blades may be polished to afford a minimum of resistance to the warp threads passing through the dents 22 of the reed as formed by laterally spacing the blades of each unit to the desired extent.

For different classes of work different reed units may be employed, with blades of relatively lighter or heavier gauge metal, and with dents of different widths between the blades.

In the present instance, for the sake of interchangeability, the reed blades 21 alternate with spacer elements 23, 24 and 25 (see Fig. 3) of proper thickness, to form the reed dents 22.

If desired, the reed blades 21, 21 may be leaded together at their opposite upper and lower ends respectively, in the manner usually followed in the formation of reed units. However, the present construction makes for interchangeability of blades in each unit as well as interchangeability of units in the loom.

In the present instance, the lower portions 21b of the blades 21 of the reed units 20 are connected to a vertically reciprocable operating bar 26, located in front of and extending substantially parallel to the lay beam 1; and the upper portions 21a of the blades 21 of the reed units 20 are vertically slidably mounted, adjacent the plane of the rear face of the lay beam 1, in guide boxes 27, 27 secured to the top rail 9.

The lower portions 21b of the blades of the reed units 20 are also slidably mounted in guide boxes 28, 28 secured to a face plate 49 rigidly mounted on the front face of the lay beam 1, above the operating bar 26.

The intermediate portions 21c of the blades of the reed units 20, in the present instance, lie above, across, and substantially parallel to the upper surface of the lay beam 1.

The lower ends of the blades 21 are connected by a bolt 29, with spacer washers 23 between the blades, and with the heads 30, 30 of eye bolts 31 at each of the opposite sides of each unit 20, whereby the lower ends of the blades may be secured rigidly together to form the unit 20.

The eye bolts 31 pass through elongated slots 32, 32 formed in the operating bar 26, and are secured therein by nuts 33, to secure each unit 20 to said operating bar 26.

The bar 26 is reciprocated vertically by a series of vertical rods 34, slidably mounted in bearings 35, 35 on the several lay arms 2, respectively. Each rod 34 is provided with a collar 36 from which projects a laterally extending pin 37.

The pins 37 project into elongated slots 38 formed in the outer ends of long arms 39 of bell-crank levers 40, which latter are pivoted at 41 to the lay arms 2 respectively. Short arms 42 of the bell-crank levers 40 are connected by links 43 to the loom frame 4, whereby, as the lay moves back, the reed units 20 will be lowered, for passage of the shuttles 10 laterally across the reed units 20, above the intermediate portions 21c of the reed blades.

As the lay moves forward, each reed unit 20 will be raised to bring the front edges of the lower portions 21b of the reed blades 21 thereof behind the weft thread b, which was laid in the open warp shed by the passage of the shuttle 10.

Continued forward motion of the lay beam 1 causes the front edges of the lower portions 21b of the reed blades to beat the newly laid weft thread b into the fell of the strip of fabric y, which strip extends forwardly over and around the breast beam 44 of the loom to take-off and

take-up rolls, or equivalent mechanisms not shown and which form no part of the present invention.

The spacer elements 24 and 25 are provided with ears 45 (see Fig. 5) which bear against the upper and lower edges respectively of the guide boxes 27 and 28, as shown in Figs. 1, 2 and 4, to maintain the spacers against longitudinal movement as the portions 21a and 21b slide freely between the spacers as the reed units 20 are raised and lowered.

With the reed blades raised, as shown in Fig. 2, the thrust of the beat up will be absorbed primarily by the face plate 49 on the front face of the lay beam 1, and the guide boxes 28 secured thereto.

However, a portion of the beat-up thrust is taken by the guide blocks or boxes 27 and top rail 9, through the upper portions 21a of the blades 21 and the intermediate horizontal portions 21c of the blades 21, as will be clear from Fig. 2.

In the structure shown in Figs. 7 and 10 the back parts 21a of the reed blades 21 are provided with lower depending parts 21d, below the horizontal part 21c, opposite and in the plane of the front lower part 21b, forming an inverted yoke which spans the top portion of the lay beam 101.

The lower ends of the depending front and rear parts 101b and 101c, respectively, are connected at 129, 129 to upstanding arms 130, 130 of a yoke member 131 which inversely spans the lower portion of the lay beam 101.

The upper rear parts 21a are slidably mounted in guide boxes 127 with spacers 125 therebetween, with the boxes secured to the top rail 109 of the lay.

The lower front parts 21b are slidably mounted in guide boxes 128, with spacers 124 therebetween, and with the boxes 128 mounted on the front plate 149 of the lay beam 101.

The lower rear parts 21d are slidably mounted in guide boxes 128a, with spacers 124a therebetween, and with the guide boxes 128a mounted on rear plates 149a on the rear face of the lay beam 101.

In the present instance the front and rear plates 149 and 149a are spaced apart to the exact thickness of the intervening portion of the lay beam 101, by sleeves 150 which surround through bolts 151 by which the guide boxes are accurately maintained in predetermined relation to each other to prevent binding of the blades in the boxes as may occur due to swelling or shrinking of the wooden lay beam 101 under abnormal conditions.

In the present instance the yoke brackets 131 are secured to operating bars 126 disposed below the lay beam 101, intermediate the lay arms 102.

The bars 126 are each reciprocated vertically by a fan of vertical rods 134, one at each of the opposite ends of each bar, with said rods slidably mounted in bearings 135, 135 on several lay arms 102, respectively. Each rod 134 is provided with a collar 136 from which projects a laterally extending pin 137.

The pins 137 project into elongated slots 139 formed in the outer ends of long arms 139 of bell-crank levers 140, which latter are pivoted at 141 to the lay arms 102 respectively. Short arms 142 of the bell-crank levers 140 are connected by links 143 to the loom frame 104, whereby, as the lay moves back, the reed units 20 will be lowered, for passage of shuttles 110 laterally

across the reed units 20, above the intermediate portions 21c of the reed blades; and, as the lay moves forward, the reed units 20 will be raised to bring the front edges of the lower portions 21b of the reed blades 21 behind the weft threads b, which were newly laid in the open warp sheds by said passage of shuttles 110.

Continued forward motion of the lay beam 101 causes the front edges of the lower portions 21b of the reed blades to beat the newly laid weft thread b into the fells x of the strips of fabric y, which strips extend forwardly over and around the breast beam 144 of the loom to the take-off and take-up mechanisms of the loom.

The depending back parts 21d, together with the upper back parts 21a, sliding in their respective guide boxes 127 and 128a assist the front parts 21b, sliding in their guide boxes 128, in resisting the pounding action of the reed blades 21 in beating the weft threads b up at the fell x of the fabric.

The lower ends of the front blade parts 21b, and the lower ends of the rear blade parts 21d, in each instance are secured together, with spacing washers 123 therebetween (see Fig. 9) by the bolts 129, 129 respectively, which also secure said blade ends to the legs 130, 130 of the yoke brackets 131.

The bolts 129, 129 are each provided with a head 129a of increased diameter slidably mounted in one of the yoke legs 130 and providing a shoulder 129b by which the assembled blade parts 21b and spacing washers 123 are pulled up tightly against the second of the yoke legs 130, to retain each reed unit 20 together as a compact interchangeable whole.

The yoke brackets 131 are secured to the operating bars 126 by bolts or screws 133 which pass through slots 132, 132 in bars 126, whereby the blades of each unit 20 may first be rigidly secured together and the brackets 131 then properly aligned with the guide boxes 128, 128a, to prevent binding of the blades therein, in operation.

It will be understood that the detail of the structure may be varied according to the ideas of individual designers without departing from the spirit of the invention; and that only such limitations as may be dictated by the prior art should be applied to the appended claims.

I claim:

1. In a loom including a laterally horizontally reciprocable lay beam and a shuttle operable lengthwise thereof to place weft threads in open warp sheds formed of warp threads extending transversely across said beam, a reed comprising vertically reciprocable blades disposed in planes transverse to said beam and spaced apart longitudinally thereof for passage of said warp threads between said blades, forward edges of said blades when the lay is in rearward position being aligned in a plane adjacent the plane of movement of the forward edge of said shuttle below the path of movement of the shuttle lengthwise of the lay and adapted to rise on a forward movement of the lay to beat-up said wefts at the fell of a fabric formed of said warps and wefts.

2. In a loom including a laterally horizontally reciprocable lay beam and a shuttle operable lengthwise thereof to place weft threads in open warp sheds formed of warp threads extending transversely across said beam, a reed comprising vertically reciprocable blades disposed in planes transverse to said beam and spaced apart longi-

tudinally thereof for passage of said warp threads between said blades, forward edges of said blades where the lay is in rearward position being aligned in a plane adjacent the plane of movement of the forward edge of said shuttle below the path of movement of the shuttle lengthwise of the lay and adapted to rise on a forward movement of the lay to beat-up said wefts at the fell of a fabric formed of said warps and wefts, and means for raising and lowering said blades intermediate the weft-placing movements of said shuttle.

3. In a loom including a lay beam and a shuttle operable lengthwise thereof to place weft threads in open warp sheds formed of warp threads extending transversely across said beam, a reed comprising blades disposed in planes transverse to said beam and spaced apart longitudinally thereof for passage of said warp threads between said blades, each blade comprising front and back rigidly united upright parts having forward edges aligned in planes adjacent the planes of movement of the forward and rearward edges respectively of said shuttle.

4. In a loom including a lay beam and a shuttle operable lengthwise thereof to place weft threads in open warp sheds formed of warp threads extending transversely across said beam, a reed comprising blades disposed in planes transverse to said beam and spaced apart longitudinally thereof for passage of said warp threads between said blades, each blade comprising front and back upright parts having forward edges aligned in planes adjacent the planes of movement of the forward and rearward edges respectively of said shuttle, and intermediate parts extending transversely of said beam and integrally connecting said front and back upright parts.

5. In a loom including a lay beam and a shuttle operable lengthwise thereof to place weft threads in open warp sheds formed of warp threads extending transversely across said beam, a reed comprising blades disposed in planes transverse to said beam and spaced apart longitudinally thereof for passage of said warp threads between said blades, each blade comprising front and back upright parts having forward edges aligned in planes adjacent the planes of movement of the forward and rearward edges respectively of said shuttle, and intermediate parts extending transversely of said beam and integrally connecting said front and back upright parts with the top edges of said intermediate parts normally in a plane adjacent the plane of movement of the lower edge of said shuttle.

6. In a loom including a lay beam and a shuttle operable lengthwise thereof to place weft threads in open warp sheds formed of warp threads extending transversely across said beam, a reed comprising blades disposed in planes transverse to said beam and spaced apart longitudinally thereof for passage of said warp threads between said blades, each blade comprising front and back upright parts having forward edges aligned in planes adjacent the planes of movement of the forward and rearward edges respectively of said shuttle, and intermediate parts extending transversely of said beam and integrally connecting said front and back upright parts with the top edges of said intermediate parts normally in a plane adjacent the plane of movement of the lower edges of said shuttle, and means for raising and lowering said blades intermediate the weft-placing movements of said shuttle.

7. In a loom including a laterally horizontally

reciprocable lay beam, a shuttle operable lengthwise thereof to place weft threads in open warp sheds formed of warp threads extending transversely across said beam, and means for moving said beam back and forth lengthwise of said warps, a reed comprising vertically reciprocable blades disposed in planes transverse to said beam and spaced apart longitudinally thereof for passage of said warp threads between said blades, forward edges of said blades when the lay is in rearward position being aligned in a plane adjacent the plane of movement of the forward edge of said shuttle below the path of movement of the shuttle lengthwise of the lay and adapted to rise on a forward movement of the lay, and means operable by the back and forth motion of the lay beam for raising and lowering said blades intermediate the weft-placing movement of said shuttle to beat-up said wefts at the fell of a fabric formed of said warps and wefts.

8. In a loom including a lay beam, a shuttle operable lengthwise thereof to place weft threads in open warp sheds formed of warp threads extending transversely across said beam, means for moving said lay beam back and forth lengthwise of said warps, a reed comprising blades disposed in planes transverse to said beam and spaced apart longitudinally thereof for passage of said warp threads between said blades, forward edges of said blades being aligned in a plane adjacent the plane of movement of the forward edge of said shuttle, a bar extending parallel to said beam, means for connecting said blades to said bar, and means operable by the back and forth motion of the lay beam for raising and lowering said bar and said blades in intermediate the weft-placing movements of said shuttle to beat-up said wefts at the fell of a fabric formed of said warps and wefts.

9. In a loom including a lay beam, a shuttle operable lengthwise thereof to place weft threads in open warp sheds formed of warp threads extending crosswise of said beam, a reed comprising laterally spaced blades extending transversely of said beam between which said warp threads pass, means for moving said beam back and forth to effect beat-up of said wefts by the forward edges of said blades at the fell of a fabric composed of said warps and wefts, a bar parallel to said beam to which said blades are attached, a bell-crank lever bodily movable back and forth with said beam, means operably connecting one arm of said bell-crank lever to said bar, and a link operably connecting a second arm of said bell-crank lever to a fixed portion of the loom, whereby said blades will be lowered and raised in coordination with the back and forth movements respectively of said lay beam.

10. In a loom including a lay beam, a shuttle operable lengthwise of said beam, a reed comprising a series of blades set crosswise of said beam and including rear vertical portions having front edges in a plane adjacent the back edge of the shuttle, front vertical portions having front edges in a plane adjacent the front edge of said shuttle, substantially horizontal portions integrally connecting said rear and front portions, means for reciprocating said blades vertically, and guide boxes carried by said beam for slidably supporting said rear portions of said blades.

11. In a loom including a lay beam, a shuttle operable lengthwise of said beam, a reed comprising a series of blades set crosswise of said beam and including rear vertical portions having front edges in a plane adjacent the back edge of

the shuttle, front vertical portions having front edges in a plane adjacent the front edge of said shuttle, substantially horizontal portions integrally connecting said rear and front portions, means for reciprocating said blades vertically, guide boxes carried by said beam for slidably supporting said front portions of said blades.

12. In a loom including a lay beam, a shuttle operable lengthwise of said beam, a reed comprising a series of blades set crosswise of said beam and including rear vertical portions having front edges in a plane adjacent the back edge of the shuttle, front vertical portions having front edges in a plane adjacent the front edge of said shuttle, substantially horizontal portions integrally connecting said rear and front portions, means for reciprocating said blades vertically, guide boxes carried by said beam for slidably supporting said front portions of said blades, and guide boxes carried by said beam for slidably supporting said rear portions of said blades.

13. In a loom including a lay beam, a shuttle operable lengthwise of said beam, a reed comprising a series of blades set crosswise of said beam and each including a substantially horizontal part above said beam, a vertical front part below said horizontal part in front of said beam, a vertical rear part below said horizontal part behind said beam, a vertical rear part above said horizontal part, means for reciprocating said blades vertically, and guide boxes for slidably supporting said vertical parts respectively.

14. In a loom including a lay beam, a shuttle operable lengthwise of said beam, a reed comprising a series of blades set crosswise of said beam and each including a substantially horizontal part above said beam, a front part depending from said horizontal part in front of said beam,

a rear part depending from said horizontal part behind said beam, a rear part projecting upwardly from said horizontal part, guide boxes slidably supporting said front and rear depending parts, 5 a yoke member under said beam and connecting said depending front and rear parts, and means for vertically reciprocating said yoke member and said blades.

15. A reed comprising a series of offset blades 10 each including a substantially horizontal beam crossing portion, a vertical rear portion above said horizontal portion, and a vertical front portion below said horizontal portion, said horizontal portion being of greater width adjacent said rear portion than at said front portion and tapering off from said rear to said front portion.

16. A reed comprising a series of H-shaped offset blades each including a substantially horizontal beam crossing portion, a vertical upper 20 rear portion above said horizontal portion, a vertical front lower portion below said horizontal portion, and a vertical rear lower portion below said horizontal portion said lower portions being spaced apart sufficiently to receive a lay beam of a loom therebetween.

17. A reed comprising a series of H-shaped offset blades each including a substantially horizontal beam crossing portion, a rear vertical upper portion above said horizontal portion, a lower 25 front and a lower rear vertical portion depending from said horizontal portion said lower portions being spaced apart sufficiently to receive a lay beam of a loom therebetween, and means adapted to pass crosswise of and beneath said beam for connecting said front and rear depending portions of all the blades of the series.

ROBERT J. BARTHOLOMEW.
